UNITED STATES PATENT OFFICE.

LEONARD HAPP AND EDWARD ADAM HAPP, OF BROOKLYN, NEW YORK.

GUARD.

Application filed June 23, 1921. Serial No. 479,813.

To all whom it may concern:

Be it known that we, LEONARD HAPP and EDWARD ADAM HAPP, citizens of the United States, and residents of the city of New York, borough of Brooklyn, in the county of Kings and State of New York, have invented a new and Improved Guard, of which the following is a full, clear, and exact description.

This invention relates to a guard for machinery and refers more particularly to a guard for speed governors, the principal object in view residing in the provision of a means for supporting the guard relative to the governor whereby the same may be readily moved to an out of way position when it is necessary to obtain adjustments of the governor or repairs thereto.

A further object resides in the provision of a guard means of the character described which is extremely simple in its construction, inexpensive to manufacture, and which is highly efficient and thoroughly reliable in its operation and purpose.

With the above recited and other objects in view, the invention resides in the novel construction, combination and arrangement of parts set forth in the following specification, pointed out in the appended claim and illustrated in the accompanying drawings, it being understood that variations and modifications which properly fall within the scope of the appended claim may be resorted to when found expedient.

In the drawing—

35 Figure 1 is a perspective view illustrating the application and use of the guard.

Fig. 2 is a vertical sectional view therethrough taken approximately on the line 2-2 of Fig. 1.

40 Fig. 3 is a perspective view of a slightly modified form of the invention.

Referring to the drawings by characters of reference, 10 designates a speed governor of any approved type mounted on a rotary shaft 11 for controlling and governing the speed thereof. The guard means for the governor consists of a conical cage 12 supported relative to the governor for axial movement with relation thereto.

50 Referring particularly to Figs. 1 and 2 of the drawings the means for supporting the cage or hood 12 consists of a shaft 13 depending from a superposed support and disposed in an axial line in prolongation of the shaft 11. The upper end of the hood has

secured thereto a sleeve 14 slidably arranged on the shaft 13 and designed to coact with an abutment 15 upon the lower extremity of the shaft. The means for raising or lowering the hood consists of a flexible element or cable 16 connected at one extremity 17 to the sleeve of the hood and trained over a pulley 18 supported from the superposed support for the shaft. By this arrangement the guard hood or cage 12 may be lifted or lowered by the cable 16 to uncover or cover the governor. In its normal covering or lowered position the hood operates to prevent the clothing from becoming entangled in the governor or in the event of breakage the flying of the weights from the governor arms or springs. The shaft 13 functions to guide the hood or guard 12 in its movements to insure the proper relative position of the same with respect to the governor. The abutment 15 serves to limit the downward movement of the hood and support to hold the same in proper relative position with respect to the guard normally.

The modified construction illustrated in Fig. 3 is especially designed where the machine is installed in a room or factory having an extremely high ceiling, or in other places where it would be impossible or impractical to suspend a shaft from above the governor. In such cases, and as illustrated in the modified form, the hood 12 is provided with tubular guide sleeves 20 extending from diametrically opposite points of its lower peripheral edge and suitable upstanding guide rods 21 are received thereby, the same being supported from their lower extremities from the machine or any other suitable support such as the bracket arms 22. The juncture of the guide rods with the bracket arms provides an abutment or stop 23 at the lower end of the guide rods with which the tubular sleeves 20 are adapted to coact to limit the downward movement of the hood. The upper extremities of the guide rods are provided with sleeves or abutments 24 which limit the upward movement of the hood and prevent its axial or accidental displacement. The head may be either raised by hand or may be attached to a flexible element, or cable 25 for the purpose of lifting the same.

It will thus be seen that a simple and inexpensive guard is provided which is movably mounted with respect to a governor whereby the same may be readily shifted ¹¹⁰

to an out of the way position for effecting repairs or adjustments to the governor elements.

Having thus described our invention what we claim is:

5 In a protective device for speed governors, a bracket secured in superposed relation to the governor, a rod depending therefrom and disposed in axial alignment with the axis 10 of the governor, a collar slidably arranged

on said rod, means supported from said bracket and secured to the collar for moving the latter with respect to the governor, and a wire guard adapted to cover said governor secured on said collar.

LEONARD HAPP.
EDWARD ADAM HAPP.
